47

Erza Whitman's, a citizen of Erza Whitman
Washing Machine

The Schedule referred to in these letters Patent
and making part of the same, containing a description in the
words of the said Erza Whitman himself, of his improve-
ment in the Washing Machine.

Be it known that I Erza Whitman of Hinslop
in the county of Kennebec and State of Maine have invented
a new and useful improvement in the Washing Machine
and that the following is a full and exact description of the
construction and operation of the said Machine as invented
or improved by me, reference being made to the accompa-
nying plate.

Fig 1. is a tub or cistern divested of its top or cover, and
a part of the staves to show the interior. B. B. are round rods
of wood forming a grating which is fixed firmly to the sides
of the tub, each side is fixed to a common upright or post,
so as to make an angle with each other.

C. is an upright post fixed upon a pivot in the centre
of the tub, to this is affixed a grating of wood as before
described, on the upper part of this shaft, is a drum or pulley
D. around which I put a strap of leather, each end of which
is nailed to a piece of plank or wood E. in the middle of
this piece of wood is placed a lever or handle, which is placed
upon an axle or wedgeon as a fulcrum.

Fig. 2. Represents the dashers or gratings of wood, de-
tached from the tub.

The mode of operation is the following, after
putting in the water and the clothes to be washed, by pushing
the handle or lever, backward and forward, the revolving
dasher D. presses first on one side of the fixed dashers B. B.

and then thrower, thus forcing and squeezing the articles to be washed as long as you please —

Churning may be also effectually and expeditiously done by this means —

Sometimes I attach a bevel gear to the upright shaft which moves the revolving dashers instead of the strap, but generally prefer the strap.

Claims — I claim as my improvement, the arrangement of the dashers and the mode of putting them in motion, as above specified —

In testimony, that the above is a true specification of my said improvement as above described, I have hereunto set my hand this fifth day of March 1833.
